VEHICLE TRAFFIC SIGNAL

Filed Oct. 5, 1940

UNITED STATES PATENT OFFICE

2,282,739

VEHICLE TRAFFIC SIGNAL

Peter S. Nielsen, Bismarck, N. Dak.

Application October 5, 1940, Serial No. 359,942

1 Claim. (Cl. 116—52)

This invention relates to a vehicle traffic signal, and it is an object of the invention to provide a device of this kind particularly designed and adapted for use in connection with a body of a closed type and wherein the signal can be manually manipulated by an occupant of the vehicle to give notice to traffic of a direction of turn or that the vehicle is about to stop.

It is also an object of the invention to provide a signal of this kind including a semaphore positioned exteriorly of the car body and having associated therewith an operating member disposed within the body, said semaphore being mounted for up and down swinging movement or outward swinging movement.

An additional object of the invention is to provide a signal of this kind including a semaphore mounted for swinging movement in selected positions to give desired traffic signals, together with means for maintaining the semaphore in an ineffective position closely adjacent to the wall of the car body.

The invention consists in the details of construction and in the combination and arrangement of the several parts of my improved vehicle traffic signal whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a view in elevation illustrating a traffic signal constructed in accordance with an embodiment of my invention and in applied position, the adjacent portion of the vehicle being shown in fragment;

Figure 2 is an enlarged detailed sectional view taken substantially on the line 2—2 of Figure 1 with certain of the parts in top plan and a second position of the semaphore being indicated by broken lines;

Figure 3 is a detailed sectional view taken substantially on the line 3—3 of Figure 2 with different positions of the semaphore indicated by broken lines.

As disclosed in the accompanying drawing, B denotes a body of a vehicle of a conventional closed type used in connection with automobiles. This body B, as herein disclosed, includes the usual side door D the lower portion of which is

of a conventional double metallic wall construction.

The outer wall 1 of the door D is provided with a suitably positioned and vertically disposed slot 2 of desired length. The inner wall 3 of the door D immediately to the rear of the slot 2 is formed to provide a relatively large recess or pocket 4.

The signalling arm or semaphore S is arranged exteriorly of the car body B and is positioned closely adjacent to the outer wall of the door D. This signalling arm or semaphore S may be of any desired configuration but of metal or such material to permit a suitably positioned magnetic plug 5 to hold the arm or semaphore S in substantially a horizontal position closely adjacent to the outer wall 1 of the door or in what may be termed an "ineffective" position. This plug 5 as is illustrated in Figure 2 is disposed through and supported by the outer wall 1 of the door D, and 10 coaxing only with the inner surface of the semaphore. The inner end portion of the arm or semaphore S is pivotally connected, as at 6, to a short plate 7. This plate 7 is also positioned at the outer side of the door D and is hingedly 15 connected, as at 8, to the outer wall 1 of the door D and at a position within the slot 2. The connection 8 allows the plate 7 to have swinging movement laterally with respect to the door D while the pivotal connection 6 permits the arm or semaphore S to have up and down swinging movement.

As the particular mounting of the magnetic plug 5 forms no particular part of the present invention a detailed illustration and description 20 of such mounting is believed unnecessary, other than to state that such mounting is of a character to eliminate the liability of the magnetic flux being dissipated throughout the body of the vehicle, and more particularly the door D.

The arm or semaphore S is continued by a tail piece 9 extending beyond the hinge connection 8 and this tail piece 9 is provided with an inwardly disposed and substantially perpendicularly related short arm 10 which passes through the vertical slot 2. The inner end of the arm 10 is continued by a perpendicularly related extension arm 11 disposed in a direction away from the hinge 8. This extension arm 11, as herein disclosed, is integrally formed with an operating handle H. This handle H has an end portion 12 extending inwardly of the recess 4 immediately adjacent an end wall 14 of the recess and the opposite end portion 15 of the handle H overlies the inner wall 3 of the door D and in close position thereto when the arm or semaphore S is in

its ineffective position as illustrated in Figure 2 of the drawing.

The traffic signal as herein comprised serves to promote safety and comfort to the driver of a vehicle especially in cold, rainy or stormy weather as the driver of the car will not be required to lower the usual window in order to give any traffic signal.

When the arm or semaphore S is swung outwardly to a position substantially at right angles to the door D as indicated by broken lines in Figure 2, notice will be given to the flowing traffic that the vehicle is about to make a left turn. If a turn is to be made to the right the arm or semaphore S can be readily swung upwardly as indicated by broken lines in Figure 3 and when a stop is to be made the semaphore or arm S can be swung into a lowered position or be oscillated up and down as also indicated by broken lines in Figure 3.

It is to be noted that these various traffic signals can be effected without the necessity of the driver of the car opening a window as the required manipulation of the arm or semaphore S can be readily accomplished from within the body B through the medium of the handle H. It is to be pointed out that the plug 5 offers no undue resistance to the desired movements of the semaphore S.

Both sides or faces of the arm or semaphore S should be highly reflective and such sides or faces may be of any color preferred.

From the foregoing description it is thought to be obvious that a vehicle traffic signal constructed in accordance with my invention is particularly well adapted for use by reason of the convenience

and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

10 I claim:

A traffic signal comprising, in combination, a wall structure having a vertically disposed slot, a plate at the outer side of the wall structure, means for pivotally mounting said plate on the wall structure adjacent to the slot, said plate having outward swinging movement with respect to the wall structure, a semaphore, means for pivotally connecting an end portion of the semaphore to the plate, said semaphore having swing movement in a direction substantially at right angles to the direction of swinging movement of the plate, the pivoted end portion of the semaphore having a tail piece extending through the slot of the wall structure, a handle connected to said tail piece, said handle being at the side of the wall structure opposite from the semaphore, and a magnetic plug carried by the outer face of the wall structure for coaction with the inner surface of the semaphore for releasably holding the semaphore in an ineffective position closely adjacent to the wall structure, said semaphore having sliding contact with the plug to allow the semaphore to be moved under strain to either side of the plug.

30 35 PETER S. NIELSEN.
